UNITED STATES PATENT OFFICE.

HENRY J. MURRAY, OF PORT RICHMOND, NEW YORK.

HAT-PRESS.

Specification of Letters Patent. Patented Mar. 14, 1916.

1,175,073.

Application filed January 14, 1910. Serial No. 537,998.

To all whom it may concern:

Be it known that I, HENRY J. MURRAY, a citizen of the United States, residing at Port Richmond, county of Richmond, and State 5 of New York, have invented certain new and useful Improvements in Hat-Presses, fully described and represented in the following specification and the accompanying drawings, forming a part of the same.

10 This invention relates to hydraulic or other fluid pressure hat presses of that class in which the hat is pressed against a die, usually heated, by means of a flexible and elastic pressing bag which is forced against 15 the hat by the pressure of the water or other fluid admitted to a pressure chamber of which the pressing bag forms one side; and the invention relates more particularly to improvements in the pressing bag and the 20 gasket which is usually employed for protecting the edge of the bag when it is clamped to the pressure dome of the machine. Pressing bags for use in these machines are commonly made of india rubber 25 and the life of a bag is comparatively short because of the strain to which it is subjected in use, the wear and tear incident to the grip of the clamping devices and the pressure of the bag against the edges of the 30 die and die support, and the high temperature of parts of the machine with which it comes in contact. The cost of providing new pressing bags forms a very considerable expense in the operation of these machines. 35 The gaskets used for protecting the edge portion of the bags are also usually made of india rubber and are of comparatively short life, and form another very considerable item of expense.

40 The object of the present invention is to provide machines of this class with rubber pressing bags and gaskets which shall be so formed as to have greater power of resistance to the wear and tear of use in the machine and to the deteriorating action of heat than the bags and gaskets heretofore in use; and to this end the invention consists in providing in or for use in a machine of this class a pressing bag, and preferably also a 45 gasket, strengthened and protected as hereinafter fully described and specifically pointed out in the claims.

50 The accompanying drawings show the principal parts of a hydraulic hat press of a well known form provided with a pressing

bag and gasket made to embody the invention in preferred form.

In said drawings, Figure 1 is a central vertical section of the upper part of the press. Fig. 2 is a sectional plan view on line 2 of Fig. 1. Fig. 3 is an enlarged detail sectional view of a portion of the pressing bag and gasket.

Referring to the drawings, Fig. 1 shows the pressure dome 10, die seat 11, and die 12, 65 of a well-known form of hydraulic hat press. The pressure dome 10 has a clamping plate or flange 13 formed around its edge and a movable clamping plate or flange 14 adapted to be drawn toward the flange 13 70 by means of tightening bolts and nuts 15. The die seat 11 is formed hollow as usual to provide a steam chamber 16, having an inlet 17 and an outlet 18 for steam for heating the die seat and die, and the die seat is 75 mounted to slide vertically on vertical rods 19 and is raised and lowered relatively to the pressure dome through the operation of suitably actuated arms 20. The pressure dome is provided with a water inlet 21 to 80 which water is supplied in the usual manner, and is also provided with an air cock 22. The die 12 is seated on the upper concave face of the die seat 11, and the upper face of the die will be of any suitable or 85 desired form to shape the hat which is indicated at a to the desired form. These parts as shown are of well known construction and may be of any suitable or desirable construction. The edge portion of the pressing 90 bag 25 is clamped between the clamping plates or flanges 13 and 14 in the usual manner, a gasket 26 being preferably placed between the bag and the lower clamping plate. A protecting sheet 27 of leather or other 95 suitable material is usually placed between the bag and the hat to protect the surface of the bag during the operation of pressing.

The pressing bag 25 is formed of india rubber or other suitable material having the characteristics of flexibility, extensibility and elasticity of rubber, and the term "rubber" as used in the claims, as applied to the pressing bag, is to be understood as including any such other material. To protect 100 and strengthen the portion of the bag which is most subjected to wear and strain in the machine and to the deteriorating action of heat, the bag is provided with a covering 105 of flexible fabric on one or both, preferably 110 of

55 well known form provided with a pressing

both, surfaces of that part of its brim portion which includes a part which is clamped between the clamping flanges and a part inside of and immediately adjacent thereto.

5 The flexible fabric preferably extends from the edge of the bag inward for a distance substantially greater than the width of the clamping flanges, and is preferably secured to the surface of the bag by being vulcanized thereto, and is preferably a woven fabric which may be of cotton or other suitable material. A circular strip of one or more pieces cut from fabric woven with an ordinary cross weave, such as canvass or duck, answers the purpose well. For use where the bag is to be subjected to extremely high temperatures, the covering fabric may be formed of asbestos. Such a covering of flexible fabric on one or both surfaces of the 20 outer part of the brim portion of the bag, while not interfering with the action of the bag in the machine, will strengthen the bag where the greatest strength is needed, that is at and adjacent to the inner edges of the 25 clamping flanges, and will protect the bag from being cut by the edges of the clamping flanges and of the die seat and by the edges of the die when the die is of a form having its upper outer edge near the clamping flanges, and will also to a large extent protect the rubber from being burned or deteriorated by contact with the heated parts 30 of the press.

It will be understood that a pressing bag 35 is frequently used in a hat press without having the gasket interposed between the bag and the lower clamping flange as shown in the drawings, and that when so used the lower surface of the outer brim portion of the bag in the position shown in Fig. 1 will come directly in contact with the lower clamping flange and with the die when the latter is of the form shown or of any form which brings its outer upper edge in position 40 to be engaged by the bag or gasket. The gasket 26, which is also made of rubber or other suitable flexible and elastic material, is made of such size or diameter as to lie between the bag and the lower clamping flange, 45 and of such width as to extend inward sufficiently beyond the inner edge of the lower clamping flange to provide a yielding support for the bag and to protect the bag from the edge of the die seat and the outer upper edge of the die or of any saddle or material 50 which may be used as a filling when dies of other forms than that shown and which require such filling are used. The lower surface, and preferably also the upper surface, 55 of the gasket is provided with a protecting and strengthening covering 29 of flexible material which extends from the outer edge of the gasket to within a short distance of the inner edge thereof, as shown in Fig. 3, 60 leaving an uncovered portion of the rubber 65

projecting beyond the covering fabric at the inner edge of the gasket. The covering fabric is preferably vulcanized to the rubber and is preferably a woven fabric of cotton, asbestos or other suitable material. The use 70 of asbestos fabric is desirable when the gasket is to be subjected to extremely high temperatures; and the strengthening and protecting of the bag and gasket with a flexible fabric of asbestos or other material having 75 high power of resistance to heat forms a feature of the invention. Furthermore the inner edge of the gasket is preferably made of tapered or beveled form so as to give with the bag under pressure and lessen the chafing 80 of the bag by the edge of the gasket.

To get the best results, the lower protecting strip of fabric on the bag and the gasket should be of such relative widths that the protecting strip of the bag will extend inside of the inner edge of the gasket, as shown clearly in Fig. 3, so that if the bag is bent downward the portion of the bag which engages the inner edge of the gasket will be protected by the fabric, and it should 85 be noted also that because of the inner edge of the gasket being free of any fabric covering, the chafing and wear on the fabric covering of the bag at this point will be less than if the fabric on the gasket extended 90 clear to its inner edge. It will be understood that dies of various forms and sizes may be used in hat presses of the class to which the invention relates and with which my improved pressing bag and gasket may be employed, and that the shape which the pressing bag will assume in the operation of the machine and the strains to which it will be subjected will vary greatly according to the shape and size of the die. A simple and 100 symmetrical form of die is shown in Fig. 1 of the drawings, with which the pressing bag takes a position in which its brim portion extends directly inward from the clamping flanges. With dies of other shapes and 105 sizes, the brim portion of the bag, especially near the clamping flanges, would take other positions and be subjected to different possibilities of wear and strain.

What is claimed is:

1. In a fluid pressure hat press, the combination with the pressure dome, the die, the die seat, and the clamping faces for securing the pressing bag to the dome, of a flexible rubber pressing bag having a protecting and strengthening covering of flexible fabric secured to one surface of that part of its brim portion which includes a part which is clamped between the clamping faces and a part inside of and adjacent thereto, the main central portion of the bag being without such covering.

2. In a fluid pressure hat press, the combination with the pressure dome, the die, the die seat, and the clamping faces for securing

- the pressing bag to the dome, of a flexible rubber pressing bag having a protecting and strengthening covering of flexible fabric secured to each surface of that part of its brim portion which includes a part which is clamped between the clamping faces and a part inside of and adjacent thereto, the main central portion of the bag being without such covering.
3. In a fluid pressure hat press, the combination with the pressure dome, the die, die supporting and heating means, and the clamping faces for securing the pressing bag to the dome, of a flexible rubber pressing bag having a protecting and strengthening covering of flexible woven fabric secured to one surface of that part of its brim portion which includes a part which is clamped between the clamping faces and a part inside of and adjacent thereto, the main central portion of the bag being without such covering.
4. In a fluid pressure hat press, the combination with the pressure dome, the die, die supporting and heating means, and the clamping faces for securing the pressing bag to the dome, of a flexible rubber pressing bag having a protecting and strengthening covering of flexible asbestos fabric secured to one surface of that part of its brim portion which includes a part which is clamped between the clamping faces and a part inside of and adjacent thereto, the main central portion of the bag being without such covering.
5. In a fluid pressure hat press, the combination with the pressure dome, the die, die supporting and heating means, and the clamping faces for securing the pressing bag to the dome, of a flexible rubber pressing bag having secured to one surface of its brim portion a protecting and strengthening covering of flexible fabric extending from the edge of the bag inward for a distance greater than the width of the clamping faces, the main central portion of the bag being without such covering.
6. In a fluid pressure hat press, the combination with the pressure dome, the die, die supporting and heating means, and the clamping faces for securing the pressing bag to the dome, of a flexible rubber pressing bag having a protecting and strengthening covering of flexible fabric vulcanized on one surface of that part of its brim portion which includes a part which is clamped between the clamping faces and a part inside of and adjacent thereto, the main central portion of the bag being without such covering.
7. In a fluid pressure hat press, the combination with the pressure dome, the die, die supporting and heating means, and the clamping faces for securing the pressing bag to the dome, of a flexible pressing bag having a protecting and strengthening covering of flexible fabric on both surfaces of that part of its brim portion which includes a part which is clamped between the clamping faces and a part inside of and adjacent thereto, and a rubber gasket between the bag and the clamping face on the die side of the bag which extends inward beyond the clamping face and which is provided on its surface toward the bag with a strengthening and protecting covering of flexible fabric which ends short of the inner edge of the gasket.
8. In a fluid pressure hat press, the combination with the pressure dome, the die, die supporting and heating means, and the clamping faces for securing the pressing bag to the dome, of a flexible rubber pressing bag having a protecting and strengthening covering of flexible fabric on the surface toward the die of that part of its brim portion which includes a part which is clamped between the clamping faces and a part inside of and adjacent thereto, and a rubber gasket between the bag and the clamping face on the die side of the bag which extends inward beyond the clamping face and which is provided on its surface toward the die with a strengthening and protecting covering of flexible fabric which ends short of the inner edge of the gasket.
9. In a fluid pressure hat press, the combination with the pressure dome, the die, die supporting and heating means, and the clamping faces for securing the pressing bag to the dome, of a flexible rubber pressing bag having a protecting and strengthening covering of flexible material on the surface toward the die of that part of its brim portion which includes a part which is clamped between the clamping face and a part inside of and adjacent thereto, and a rubber gasket between the bag and the clamping face on the die side of the bag which extends inward beyond the clamping face, the fabric on the bag extending inward beyond the edge of the gasket.
10. In a fluid pressure hat press, the combination with the pressure dome, the die, die supporting and heating means, and the clamping faces for securing the pressing bag to the dome, of a flexible rubber pressing bag, and a rubber gasket between the bag and the clamping face on the die side of the bag which extends inward beyond the clamping face and which is provided on both its upper and lower surfaces with a strengthening and protecting covering of flexible fabric.
11. In a fluid pressure hat press, the combination with the pressure dome, the die, die supporting and heating means, and the clamping faces for securing the pressing bag to the dome, of a flexible pressing bag having a protecting and strengthening covering of flexible fabric on both surfaces of that part of its brim portion which includes a part which is clamped between the clamping faces and a part inside of and adjacent thereto, and a rubber gasket between the bag and the clamping face on the die side of the bag which extends inward beyond the clamping face and which is provided on its surface toward the bag with a strengthening and protecting covering of flexible fabric which ends short of the inner edge of the gasket.

to the dome, of a flexible rubber pressing bag, and a rubber gasket between the bag and the clamping face on the die side of the bag which extends inward beyond the clamping face and which is formed of a body of rubber provided on its surface toward the pressing bag with a strengthening and protecting covering of flexible fabric which ends short of the inner edge of the gasket.

12. In a fluid pressure hat press, the combination with the pressure dome, the die, die supporting and heating means, and the clamping faces for securing the pressing bag to the dome, of a flexible rubber pressing bag, and a rubber gasket between the bag and the clamping face on the die side of the bag and which has a body of rubber formed with a beveled inner edge and having on its wider surface a protecting and strengthening covering of flexible fabric which ends short of the inner edge of the gasket.
13. A flexible rubber hat pressing bag for

a fluid pressure hat press, having on one surface of its brim portion a protecting and strengthening covering of flexible fabric extending from the edge of the bag inward for a distance greater than the width of the clamping devices by which the bag is to be held.

14. A flexible rubber hat pressing bag for a fluid pressure hat press, having a protecting and strengthening covering of flexible fabric on both surfaces of that part of its brim portion which includes a part which is intended to be clamped between clamping devices of a hat pressing machine and a part inside of and adjacent thereto.

In testimony whereof, I have hereunto set my hand, in the presence of two subscribing witnesses.

HENRY J. MURRAY.
